WORK SUPPORT

John F. Standish, Winthrop, Mass., assignor to
 United Shoe Machinery Corporation, Flemington, N. J., a corporation of New Jersey

Application February 5, 1945, Serial No. 576,339

14 Claims. (Cl. 12—126)

1

This invention relates to supports upon which work may be mounted for operations upon it, it especially concerning those supports employed in the attachment of heels to shoes.

In a known heel-attaching machine in which a single nail is driven through the heel-seat of a lasted shoe into a heel positioned upon the heel-seat, the work is supported upon a jack having a tubular spindle received in a passage through the rear of the last-cone, the nail-driver operating through the spindle. To hold the work in a definite relation to the driver, the end of the spindle may be engaged either by the insole of the jacked shoe or by an overhanging shoulder furnished by the last-plate, in which is an opening of less diameter than that of the last-passage and through which the driver acts in inserting the nail. In the first case, when pressure is applied to the work to resist the nail-driving force, the spindle tends to indent and deform the insole. In the second case, it may mutilate or destroy the last-plate-shoulder. An object of my invention is to remove entirely the clamping pressure from the spindle or like supporting member, while still maintaining its engagement with the work, at the same time correctly locating and stably supporting said work. To this end, I provide two movable supporting members, at least one of which is movable under the influence of the work. With these members is combined means for retaining one of them against movement during movement of the other, and then freeing the retained member and retaining the other against movement. The first of these members may be the last-entering spindle of a heel-attaching machine, and the second a bed-piece arranged to receive engagement of the crown of the last-cone. With the two members yieldable under engagement of the work, by initially locking one the work may be positioned properly for the operation to be performed upon it, while the other member is being located by the work. Then, by releasing the first member, it is relieved of the pressure to be applied, yet is maintained in contact with the work, and by locking the second member, which has yielded during the first stage of operation, the work is held firmly as positioned for the operation upon it. The locking and releasing of the members is preferably controlled by the position of the support, there being means acting during the movement of said support to effect the change. One member, as the spindle, is locked in the work-receiving position of the support and unlocked as it travels to the operating position, the reverse being true for the second

2

member or last-bed-piece. More specifically, my improved work-support or jack has a base slideable between the two positions, and depressible in which, by engagement of the work, are a last-spindle and a last-bed-piece. As illustrated, this spindle is held up initially by a track extending along the path of the jack and freed before the operating position is reached. The last-bed-piece is carried by an hydraulic device, in a manner usable in other connections than in association with a last-spindle. This device includes a piston carrying the last-bed-piece and operating in a cylinder under the control of a valve, which may be actuated by a track similar to that governing the spindle.

15 In the accompanying drawings,

Fig. 1 is a central vertical longitudinal section through one embodiment of my invention, showing the jack in its work-receiving position;

20 Fig. 2, a similar view with the jack in operating position;

Fig. 3, a vertical transverse section, taken at the center of the last-bed-piece;

Fig. 5, a similar view of the means for limiting the travel of the jack; and

Fig. 6, a like view of the controlling means for the last-spindle.

30 The work-support of this invention is herein disclosed as applied to a heel-attaching machine, in which a plunger 10 reciprocated under power in a frame-column 12 actuates a driver 14, guided in a jack J to insert a nail N through the heel-seat of a jacked shoe S into a heel H. The shoe is carried by a last L provided with a last-plate l. In the last is a passage x inclined forwardly from the rear of the crown of the last-cone to the heel-seat-portion. The last-plate is shown as having a shoulder l' overhanging the end of the passage. The heel is clamped in place upon the heel-seat of the shoe to receive the action of the driver by a hold-down device P, reciprocated under the power of the machine. Attached to the top of the column 12 is a cap 16, elongated fore and aft of the machine and provided with opposite ways 18, 18 inclined downwardly and rearwardly. Guided in the ways is the plate-like base 20 of a vertical jack-body 22. The work-receiving position of the jack, as it appears in Fig. 1 of the drawings, is determined by contact of an upward projection 24 upon the base with a stop-plate 26 secured to the frame-cap (Fig. 5). Rearward movement to the operating position (Fig. 2) is limited by the engagement of the edge 28 of the

jack-base with a crossbar 30 fixed to the frame. The rearward, downward inclination of the ways 18 tends to ensure the full movement of the jack to this position.

Through the rear of the jack-body is an upwardly and forwardly inclined passage 32, having reciprocating in it an inclined tubular spindle 34, in which the driver 14 is guided for reciprocation. The spindle is adapted to receive the last-passage x and is held yieldably up by a tension-spring 36 joining projections from the jack-body and from a foot 38 clamped upon the spindle by a screw 40 (Fig. 6). The upward movement of the spindle is limited by engagement of the surface 42 of the foot with an opposed surface upon the jack-base. Adjustment of the foot upon the spindle, of which it may be considered to be a part, permits the upper extremity of said spindle to be located at such a height that it will support a lasted shoe in a definite relation to the driver 14. Therefore, in the reciprocation of the driver, the head of the heel-attaching nail N which it carries will be sunk properly in the insole. The driver is held against downward displacement in the spindle-passage in its normal position by a key 44, fitting an opening in the spindle-wall and lying at its inner edge in a key-way 46 extending longitudinally of the lower portion of the driver. The outer edge of the key lies in a slot 48 in the jack-body. In this slot, the key will move during depression of the spindle. When the jack is in its forward work-receiving position, the spindle 34 is locked against depression by contact of transversely extended portions 50, 50 of its foot 38 with tracks 52, 52. These tracks are bridged together at 53 and are inclined downwardly and rearwardly at the same angle as the ways 18. The bridge-piece is secured to the front of the cap 16 for vertical adjustment by slot-and-screw connections 54. By this adjustment, the tracks may be brought into the proper relation to the foot of the spindle, for any adjustment of said foot which has been made to locate the upper end of the spindle. After a certain extent of movement of the jack-base toward the operating position, the tracks 52 end, and the spindle-foot runs off above a lowered portion 56, which frees the spindle for depression but still prevents undue downward displacement. The work now receives the support of another member, as described below.

In the jack-body 22 a vertical cylinder 58 is formed. In the cylinder operates a tubular piston 60, having in an enlargement 61 at its top a segmental depression 62, which receives the complementary under surface 64 of a bed-piece 66 for which the piston is a carrier. The cylinder, with the piston, may be considered as portions of the base. The central portion of the segment 66 is shown as removed, the hollow thus produced being surrounded by an annulus which is wedge-shaped in transverse section. As a result of this, the descent of the holdown P initially causes the positioning of the bed-piece at the proper angle. Then, as the clamping pressure goes on, the effect of the wedge is to lock said bed-piece against displacement. The plane upper surface 68 of the bed-piece is adapted to support the last L by contact with the crown-surface 70 of its cone. The spindle 34 passes through a radial slot 72 in the bed-piece. The piston and bed-piece are urged normally up by two expansion-springs 74, 74, surrounding rods 76, 76 depending from the piston-enlargement 61 through openings in the jack-base 20. These springs are interposed between the piston-enlargement and the base,

and upward movement of the piston, produced by the springs, is limited by the contact of nuts 78 threaded upon the lower ends of the rods with the underside of the base. The lower end of the piston carries a valve-seat 80, in an axial upward extension 82 of which the stem 84 of a valve 86 is movable. An expansion-spring 88 between the extension and a flange 90, below a splash-disk 92 secured to an enlargement 93 upon the upper end of the stem, tends to close the valve, and thus the passage through the piston. When this occurs, the piston is locked against depression by a body of non-compressible liquid, such as oil, contained in the cylinder. In the work-receiving position of the jack (Fig. 1), the valve is held open by a bell-crank-lever 94 (Figs. 3 and 4), fulcrumed at 96 on the piston-enlargement 61. One arm 98 of the lever extends between the flange 90 and the enlargement 93, it being forked to receive the valve-stem. The opposite arm 100 of the lever has a depending portion, movable in the travel of the jack along a track 102 parallel to the ways 18 and extending from a bracket 104 attached to the cap 16. With the jack in work-receiving position, the track engages the arm 100 and actuates the lever to lower the valve from its seat. The position of the nuts 78 upon the rods 76 permits the springs 74 to so elevate the piston 60 and last-bed-piece 66, that, when the plate l of the last having the lowest cone contacts with the end of the locked spindle 34, the engagement of the crown of the cone with the last-bed-piece at least slightly lowers the unlocked piston. When the jack is shifted rearwardly by the operator into operating position, the lever-arm 100 leaves the track 102, it lying opposite a reduced portion 106 with which said arm does not contact. The valve is now closed by its spring 88, and the piston and last-bed-piece are locked in preparation for the heel-attaching operation.

Considering the action of the jack J through a heel-attaching cycle, initially the base 20 is forward in its ways 18 in the position of Fig. 1, fixed by the engagement of the projection 24 with the plate 26. The foot 38 of the tubular spindle 34 rests upon the tracks 52, and the spindle is therefore locked against depression. The operator drops a nail-head-down into the passage of the spindle, places over the spindle the passage x of a last L bearing a shoe S, and positions a heel H upon the heel-seat of the shoe. Since the arm 100 of the lever 94 is in engagement with the track 102, the valve 86 is open, the piston 60 and last-bed-piece 66 being raised to the maximum extent by the springs 74, (as shown in Fig. 3). The descending crown of the last engaging the bed-piece carries this down with it against the force of the springs. This continues until the movement is stopped by contact of the last-plate-shoulder l' with the end of the locked spindle, (as shown in Fig. 1). There has thus been determined the distance of the insole of the shoe from the end of the driver 14 contained in the spindle, and the height of the last-cone has been measured by the depressed last-bed-piece. The operator now slides the jack back until it is stopped by the bar 30, the work thereby being located in operating position. Before the spindle-foot 39 leaves the track 52, the lever-arm 100 passes off the track 102. The valve 86 is, therefore, closed by the spring 88, trapping the oil beneath the piston 60 and locking this against depression. Then, the passing of the spindle-foot from the track over the depressed portion 56 frees the spindle. Consequently, the last-bed-

piece now furnishes a rigid support for the work, except as angular accommodation is allowed by the universal rocking movement of the bed-piece in the depression 62. The power-operation of the machine is now started, the device P descending to clamp the work upon the bed-piece, and the driver 14 rising under the influence of the plunger 10 to insert the nail which it carries through the heel-seat of the shoe into the heel. At this time, the spindle is held up only by the spring 36 and is, therefore, subjected to no clamping pressure transmitted through the last-plate-shoulder 1'. even were there some downward yield of the work to occur. The spring does, however, maintain the end of the spindle yieldably in close contact with the last-plate, so there is between the spindle and the plate no space into which any portion of a nail may pass. In prior machines of this type, the nail tends to slide laterally upon the end of the driver, so the edge of the head enters between the end of the spindle and the shoulder of the last-plate. When the spindle is fixedly supported, the pressure which the nail-head exerts against the shoulder will gradually wear away said shoulder, so the spindle will pass through the last. This necessitates replacement of the last-plate. During the completion of the operating cycle of the machine, the driver descends to its normal position, the pressure device rises to free the work, and the operator draws out the jack and removes the shoe with its attached heel.

It will be seen that in this support there are provided a member which supports the work to locate it accurately in preparation for the operation upon it, and a second member which measures the positioned work and then furnishes the final pressure-receiving support, the first member functioning only as directing means without work-pressure. Further, the transfer of action between the two members is effected by simple and effective means, controlled automatically during the travel of the support in its customary reciprocation between the work-receiving and operating positions.

Having described my invention, what I claim as new and desire to secure by Letters Patent of the United States is:

1. A support into cooperation with which work is moved and comprising two movable work-supporting members at least one of which is moved by the work, means for retaining one of the members against movement during movement of the other, and means for freeing the retained member and for retaining the other member against movement.

2. A support engaged by work and movable between two positions, said support comprising two supporting members movable independently of each other by the engagement of the work, means for retaining one of the members against movement during movement of the other, and means acting during movement of the support for freeing the retained member and for retaining the other member against movement.

3. A support comprising a yieldable work-supporting member, means for locking the member in position to locate the supported work, a supporting member yieldable while the work is being thus located, and means for freeing the first member and locking the second member after the location of the work.

4. A jack comprising a base, a last-spindle and a last-bed-piece-carrier movable upon the base by the application of a last to the jack, means for locking the spindle against movement, and

means for locking the carrier against movement.

5. The combination with a frame, of a jack-base movable between work-receiving and operating positions, a last-spindle and a last-bed-piece-carrier movable upon the base, locks for the spindle and carrier, and means for controlling the effect of the locks upon the spindle and carrier in the movement of the base between work-receiving and operating positions.

6. A jack comprising a base movable between work-receiving and operating positions, a last-spindle movable upon the base, means for locking the spindle against movement in work-receiving position, a last-bed-piece-carrier movable upon the base in work-receiving position, means for locking the carrier upon the base in the movement of the base toward operating position, and means for releasing the spindle from its locking means upon movement of the base toward operating position.

7. The combination with a frame, of a jack-base slidable thereon between work-receiving and operating positions, a last-spindle yieldable in the base, a track by which the spindle is held against depression in the work-receiving position of the base and is released when in the operating position, a last-bed-piece-carrier yieldable upon the base, and means including a track by which the carrier is left free for depression in work-receiving position and is held against depression in the operating position.

8. The combination with a frame, of a jack-base movable thereon, a work-supporting member movable upon the base by engagement of the work, and means made effective during the travel of the base for locking the work-supporting member against movement.

9. The combination with a frame, of a jack-base movable thereon, a work-supporting member movable upon the base by engagement of the work, and hydraulic means made effective during the travel of the base for locking the work-supporting member against movement.

10. A jack comprising a base, a work-engaging member movable upon the base, an hydraulic device by which the work-engaging member is positioned, a valve by which the hydraulic device is controlled, and means for operating the valve.

11. A jack comprising a movable base, a cylinder carried by the base, a piston movable in the cylinder, a last-bed-piece carried by the piston, a valve by which movement of the piston is controlled, means tending to close the valve, and means for holding the valve initially open and freeing it for closure in the movement of the base.

12. The combination with a frame provided with ways, of a jack-base slidable in the ways between work-receiving and operating positions, a last-spindle and a last-bed-piece movable on the base, and tracks extending along the ways and by which the movements of the spindle and bed-piece are controlled.

13. The combination with a frame provided with ways, of a jack-base slidable in the ways between work-receiving and operating positions, a last-spindle and a last-bed-piece movable on the base, means for yieldably elevating the spindle and bed-piece for engagement by the work, and tracks extending along the ways and respectively provided with portions for controlling the spindle at the work-receiving position and the bed-piece at the operating position.

14. The combination with a frame provided with ways, of a jack-base slidable in the ways between work-receiving and operating positions, a

last-spindle yieldable in the base, a cylinder carried by the base, a piston yieldable in the cylinder and provided with a passage, a last-bed-piece carried by the piston, a valve by which the piston-passage is controlled, a lever fulcrumed upon the piston and engaging the valve, means tending to normally elevate the spindle, means tending to normally elevate the piston, and tracks arranged for engagement by the spindle and lever, respectively, during movement of the jack-base.
